CORNER MOUNT

John R. Condon, Reading, Mass.

Application June 7, 1939, Serial No. 277,831

7 Claims. (Cl. 40—158)

This invention relates to corner mounts for supporting pictures and the like in books and albums, and to a novel method of making the mounts. Such mounts have been known and used for many years and the primary object of my invention is the production of a new and improved mount for this purpose and of a novel method of making the same more efficiently and economically.

My improved mount is made from a relatively narrow paper strip preferably gummed on both sides and, in accordance with the invention, the strip is scored at uniformly spaced positions therealong to provide two fold lines thereacross at each such position, the area between each two lines forming the body portion of a mount. A substantially triangular facing cap is adhesively attached to each such area, the facing cap preferably being cut from a second strip and immediately applied to the body and forming, in combination with the body, an open pocket adapted to receive the corner of a picture to be supported. The first strip is therefore severed at positions leaving two predetermined lengths of the strip attached to opposite sides of each body, these lengths being then folded backwardly onto the body along the scored lines to form a base for attaching the mount adhesively to its supported sheet in the album. The scored lines are so arranged that the folded lengths or legs are parallel and directly adjacent to each other and a further feature of the invention resides in applying a paper tie adhesively thereto, the ties preferably being cut from a third strip and applied directly to the two legs. The production of the novel method embodying these steps and the superior mount thus produced comprises further objects of the invention.

A further feature of the invention resides in so cutting and perforating the cap layer of each mount that a portion thereof can be readily detached by the user whereby changing the mount from a wide margined type to a narrow margined type, the mounts and methods heretofore known requiring these two types to be made and sold independently.

These and other features of the invention will be best understood and appreciated from the following description of preferred embodiments thereof selected for purposes of illustration and shown in the accompanying drawing in which,

Fig. 1 is a side elevation of the mechanism employed in making my improved mounts,

Fig. 2 is a plan view showing such mechanism in operation on a strip of material,

Fig. 3 is a front elevation of one of the formed mounts in folded condition,

5 Fig. 4 is a side elevation of mechanism for applying a tie adhesively to each mount,

Fig. 5 is a plan view thereof,

Fig. 6 is a front elevation of a finished mount,

10 Fig. 7 illustrates a narrow margined mount formed by detaching a portion of the cap from the mount shown in Fig. 6,

Fig. 8 illustrates the detached portion of the cap,

15 Fig. 9 is a sectional view taken on line 9—9 of Fig. 6, and

Fig. 10 is a bottom plan view of a block supporting the male dies shown in Fig. 1.

The body portion of my improved mount is made from a paper strip 10 preferably gummed 20 on both sides. The strip is fed by intermittent steps to adjacent dies 12 and 14 and to a cutting off die 15. Superposed over the die 14 is a female die 18 and cooperating with the dies 12, 14—18, and 15 are male dies 20, 21 and 22. 25 In practice, these dies may be more closely spaced and may be mounted in a single block 24, Fig. 10 being a bottom plan view of such block with the dies 20, 21 and 22 mounted therein.

The die 20 is provided with a V-shaped cutting 30 edge 26, a V-shaped creasing edge 27, and a V-shaped perforating edge 28 between and parallel with the edges 26 and 27. The die 12 is constructed to cooperate with the die 20 to the end that (1) the edge 26 cuts out V-shaped portions of the strip at 30, (2) the edge 27 creases the strip along two scored fold lines 32 parallel with the edges of the notch 30, the lines 32 converging toward and meeting at one edge of the strip with approximately a 90° angle therebetween, and (3) the edge 28 perforates the strip along a V-shaped line 33. Each such treated area of the strip is designated by reference character 34.

The die 21 is provided with an unbroken cutting edge therearound including V-shaped cutting edges 35 and 36 corresponding to the edges 26 and 27 of the die 20, and the female die 18 has a die opening 37 therethrough of a corresponding shape to fit such unbroken cutting edge.

50 At each upward movement of the dies 20, 21 and 22, the strip is advanced the distance between adjacent areas 34 whereby such areas are consecutively located on the die 14 directly beneath the opening 37. A second strip 38 of suitable paper or the like is fed intermittently across

the opening 37 in the die 18 and, upon each downward movement the die 21 cuts a facing cap 39 from the strip 38 and carries it to the area 34. The die 21 is furthermore provided with a cutting edge 40 for cutting the cap along a V-shaped line 41 slightly forward of the perforations 33 and with any suitable embossing design which it is desired to impart to the face of the cap. The bottom face of the strip 38 is moistened, as by a moistening roller 42, whereby it adheres to the gummed area 34 when pressed into contact therewith, it being understood that the embossing of the cap and cutting thereof by the edge 40 are performed by pressure of the die 21 on the cap and against the die 14.

The dies 22 and 15 are so spaced from the die 21 that they sever the strip midway between adjacent areas 34 and these dies have zig-zag cutting edges which form each cut end of the strip with one full middle tooth 44 and two half teeth 45 at opposite sides thereof. The individual mount units thus formed are next folded along the creased lines 32, the end portions 46 being folded backwardly onto the strip whereby forming the unit into a body and two attached legs. Such folding operation will be performed automatically by suitable mechanism.

The folded units, illustrated in Fig. 3, are next fed onto a die 48 beneath the opening 50 in a female die 52. A strip 54 of suitable paper or the like is fed intermittently across the top face of the die 52 and over the opening 50, and a male die 56 operates thereon to cut a tie piece 58 from the strip and force it into adhesive contact with the mount. The bottom face of the strip 54 is moistened as it passes onto the die 52 and the mount is so located that the tie 58 bridges across the two legs 46 and ties them together, the two inner half teeth being thereupon combined so as to provide three full teeth between two outer half teeth 45.

The finished mount is illustrated in Fig. 6. The facing cap of this mount is relatively wide and corresponds to the wide margined corner mount heretofore known. If the user of the mount prefers a facing cap of the narrow margined type, he merely detaches the portion 60 along the perforated line 33 whereupon the mount becomes the narrow margined mount shown in Fig. 7. Particular attention is directed to the fact that the cutting of the cap along the line 41 slightly forward of the perforations 33 provides a clean edge on the facing cap (Fig. 7) void of any roughness which might result from removing the portion 60 along the perforated line 33. My invention therefore provides a novel mount which serves the uses of both wide and narrow margined purposes for which independent mounts have heretofore been required.

It is noted that my improved mount provides a substantial body area for adhesively receiving the facing cap 39 whereby forming a strong body and a full and deep pocket adapted freely to receive and accurately fit the corners of pictures to be mounted. When mounting a picture, a corner mount is first fitted to each corner thereof. Prior to placing each mount on the picture, the tips of the teeth 44 and 45 are moistened at their front faces, and these are pressed into holding contact with the rear face of the picture as each mount is accurately positioned thereon. The tip moistening is very conveniently performed by grasping the mount (Figs. 6 and 7) between thumb and finger and drawing the front faces of

the tips of the teeth 44-45 over and in contact with a moistening surface. The picture, with the corner mounts thus attached, is then placed in the desired position in the album, the rear faces 5 of the mounts being previously moistened, and the mounts are pressed into adhesive contact with the supporting sheet. The picture is thus positively and perfectly aligned since displacement of the mounts relative to the picture is prohibited. In case it is desired to change pictures after mounting, the relatively small adhesive attachment of the teeth 44 and 45 to the corners of the picture can be broken and the picture removed from the corner mounts and another substituted therefor, the adhesive coating being sufficient to permit these substitutions repeatedly.

It will be apparent that the coating of adhesive on both faces of the strip 10 serves several important functions as follows: (1) the adhesive on the front face of the strip 10 adapts this face to receive the cap cut from the strip 38 merely upon the moistening of the strip 38 at 42, and (2) provides the adhesive on the rear face of the finished mount; (3) the adhesive on the rear face of the strip 10 provides the adhesive along the front face of the teeth 44 and 45 for temporarily attaching the mount to the picture, and (4) provides adhesive for the entire front face of the mount for permanently attaching the mount to the picture.

Mounts heretofore known have not been gummed on their front faces but have depended upon friction to hold the mounts properly placed on the corners of the pictures. This has resulted in very objectionable displacement of the mounts relative to the picture when mounting the combined mounts and picture on the supporting sheet of the album, whereby resulting in considerable misalignment of pictures relative to the corner mounts and relative to the album. The application of adhesive to the front faces of my improved mounts, together with the teeth 44 and 45 across the edge portion opposite to the picture receiving corner, serves to provide positive and perfect mounting alignment of corners with pictures or like material. When it is desired to secure the pictures permanently or against removal, the entire front faces of the mount can be moistened and the picture pressed into contact therewith.

Having thus described my invention what I claim as new and desire to secure by Letters Patent is:

1. A paper corner mount comprising a body layer substantially in one plane and a substantially triangular pocket-forming layer in another plane and attached thereto along two converging edges of the mount, the pocket-forming layer being perforated along two lines parallel with said converging edges whereby a portion of the pocket-forming layer can be detached.

2. A corner mount comprising a strip of paper having the two end portions thereof folded backwardly onto the strip along two straight lines converging toward and meeting substantially at one edge of the strip with substantially a 90° angle therebetween and forming a body and attached legs providing a pocket therebetween, a facing cap applied adhesively to the top face of said body and the cap being cut and the body being perforated respectively along two relatively spaced lines having their ends at the strip edge opposite to said angle whereby the portion of the cap and body thus enclosed can be detached,

the said perforated line being slightly to the rear of the cut line.

3. A corner mount comprising a strip of paper having the two end portions thereof folded backwardly onto the strip along two straight lines converging toward and meeting substantially at one edge of the strip whereby forming a body and attached legs providing a pocket therebetween, a facing cap applied adhesively to the top face of said body and the cap being cut and the body being perforated along lines parallel with said straight lines and extending from the strip edge opposite to the angle formed by the converging ends of said lines to an intersecting point within the body, the said perforated lines being slightly to the rear of the cut lines.

4. A corner mount comprising a strip of paper having the two end portions thereof folded backwardly onto the strip along two straight lines converging toward and meeting substantially at one edge of the strip whereby forming a body and attached legs providing a pocket therebetween, a facing cap applied adhesively to the top face of said body, the cap and body being cut out to form a notch therein open at the strip edge opposite to the angle formed by the converging ends of said lines, and the cap being cut and the body being perforated along lines parallel with said straight lines and extending from the notched edge of the strip to an intersecting point within the body, the said perforated lines being slightly to the rear of the cut lines.

5. A corner mount comprising a single paper strip folded onto itself along two straight lines extending thereacross and converging toward one edge of the strip with approximately a 90° angle therebetween and forming an open pocket between the two layers within said angle, the layer outside of the lines having a coating of adhesive on its rear face and the other layer being perforated along a line having its ends at the strip edge opposite to said angle whereby the portion of said other layer thus enclosed can be detached.

6. A corner mount comprising a strip of paper coated with an adhesive on both faces and having the two end portions thereof folded backwardly onto the strip solely along two straight lines converging toward and meeting substantially at one edge of the strip and forming a body and attached legs providing a pocket therebetween and having adhesive surfaces for attaching the legs to a picture and the mount to a supporting surface, the body being a continuous and single intermediate portion of said strip, one adhesive face of the strip providing an adhesive surface on the front face of the mount for adhesively receiving a facing cap and providing an adhesive surface on the rear face of the mount for adhesively applying the mount to a mounting surface, and the other adhesive face of the strip providing an adhesive surface on the front face of the mount for adhesively receiving and holding a picture thereto.

7. A corner mount comprising a single paper strip folded onto itself solely along two straight lines extending thereacross and converging toward one longitudinal edge of the strip with approximately a 90° angle therebetween and forming two layers and an open picture receiving pocket therebetween and within said angle, a facing cap applied adhesively to the front face of the top layer over the pocket, the bottom layer comprising the two ends of the strip arranged in substantially parallel relation, means connected to one of the legs and in adhesive contact with the other leg for tying the two legs together, the extreme end portions of the legs located opposite to the picture receiving pocket being cut to form a plurality of teeth projecting therefrom in a direction away from the pocket and the tip portions of the teeth being adhesively gummed on their front faces to receive flatly and adhesively thereagainst a picture to a corner of which the mount is applied, and a coating of adhesive on the rear face of the mount.

JOHN R. CONDON.
